FOUNDATION MEMBER

Daniel Ganz and Irving Kaplan, Bronx, N. Y.

Application June 4, 1940, Serial No. 338,684

2 Claims. (Cl. 154—46)

This invention relates to foundation members. An object of the invention is to furnish a new article of manufacture comprising a foundation member having plastic elements connected thereto by being permanently directly bonded into the member by penetration thereof, for ornamental or utilitarian purposes or both.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary plan view of a sheet member having plastic elements bonded thereto according to one embodiment of the invention.

Fig. 2 is an enlarged edge view thereof, with a part in section to show the plastic bond.

Fig. 3 is an enlarged fragmentary sectional view illustrating an apparatus for constructing new articles and showing further details in the bonding of the plastic element to a perforated or foraminous foundation member.

Fig. 4 is a similar view of a modified apparatus embodying the invention according to an improved method of operation.

Figs. 5 and 6 are similar views of further modifications.

Fig. 7 is an enlarged plan view of a foundation member and plastic element showing an embodiment of the invention as constructed according to Fig. 4.

Fig. 8 is a fragmentary diagrammatic plan view of a die member according to the invention.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 11 denotes an article of manufacture embodying the invention. The same may include a foundation member 12 having plastic elements 14, directly plasti-

cally bonded together. The term foundation member as used herein may include knitted, and woven or textile fabrics of cotton, silk, wool, rayon, metal or composition materials, considered as sheet members. These materials and the forms thereof referred to may be further described as adapted for direct plastic bonding to the plastic material. Hence they may be porous or penetrable, or foraminous in whole or in part. In molding plastics by injection, the extremely high pressure used may affect the available penetrability of the foundation member. The plastic itself may be of any well known kind, particularly of the type which is generally used in injection molding. The plastic elements 14 may be of any suitable size and shape, and of varied spacing, arrangement and color or according to a required design for ornamentation of the foundation member; but they may also be used for functional purposes, as to protect or reinforce parts of the foundation member.

To clearly illustrate a particular advantage of the invention, the article 11 will be considered, for instance, as a fabric to be used in the making of a ladies' handbag, with the foundation member consisting of any usual textile fabric which in untreated form is necessarily porous or penetrable. Such a fabric may be defined as a closed mesh fabric. Ornamentation of ladies' handbags is always a problem and a source of considerable expense. For example, consider beaded handbags. With the present invention, an effect similar to that of a beaded handbag is available at substantially reduced cost. In so using the article 11, the elements 14 penetrate the fabric 12 and form a projection or anchorage 14a at the rear face of the fabric, but this projection should have as little depth as possible to keep down the total thickness of the article. The detailed structure will be further understood after the description hereinafter of the method of molding the plastic elements such as 14.

In Fig. 3 is shown a novel die 21, illustrating also a method of the invention. This die 21 as well as the others shown in Figs. 4 to 6, inclusive, may be arranged as shown in plan in Fig. 8 for the simultaneous molding of a great many plastic elements. It will suffice to first consider the molding of the individual plastic element. It will be seen that the die 21 may comprise a plurality of die members 22, 23, the former of which may have a die cavity 24, and the latter of which may have a feed passage or gate 25. The confronting faces of the die members are otherwise plane so as to be adapted to uniformly tightly

clamp therebetween in plane condition a foundation member or cloth 26 which forms a seal or gasket for the mold. Plastic material is fed through the gate 25 and penetrates and passes through the fabric 26 to fill into the cavity 24.

The pressure of the plastic will cause the foundation member, acting as a diaphragm, to tightly stretch and deflect somewhat into the cavity 24 as shown so that molded element 28 will be formed with an anchorage portion 29 at the rear face of the fabric substantially plane with the foundation member. Upon opening the die, the article may be removed and the adherent portion 30 at the gate broken off as at 30a. Where the cross hatching of the plastic is over the cross hatching of the fabric, complete penetration of the latter by the plastic is indicated.

For very heavy fabrics, the same may have been initially perforated as at 27, but this is not desirable, as it increases the cost and requires careful alinement with the die cavities.

In order to mold a large number of the plastic elements such as 14 or 28, it is desirable that the gates 25 shall horizontally intersect certain portions of the die cavities. If the plastic molded elements be quite small, it would be desirable that the gates extend diametrically of the cavities as suggested in Fig. 8. Hence there is a substantial area of contact between the gate molded portions 30 and the foundation member 26, and if this plastic penetrated into the foundation member 26, it might result in marring the appearance or causing discoloration of the front face of this member. Hence it is desirable, in the case of a cloth-like foundation member that it have an opening or openings to permit the use of a minimum pressure on the plastic, which pressure may be insufficient to cause the plastic to penetrate to the extent of passing entirely through the fabric. It will be appreciated that, in aid of this desired result, the fabric at the cavity 24 is unsupported at its faces, thus facilitating the flow of plastic. The dies of Figs. 4 to 6 follow the principles discussed in connection with Fig. 3, except as otherwise described. In general, it will be noted that the plastic at the cavities contacts both sides of the foundation member and hence can penetrate the same before penetration can occur at the restricted compressed portions between the contacting faces of the die members.

In Fig. 4 is shown a die 31 having a die member 22 and a companion die member 32 which may be like that at 23, except that it may have a cavity 33 of less depth than the cavity 24, and a pin 34 fixed to the die member 32 in central relation to the cavities 33 and 24. This pin may extend only partially into the cavity 24 and it may be adapted to pierce the foundation member 35. Preferably the pin may be in the form of a blade or pyramid to afford longitudinal edges for cutting the foundation member to produce an enlarged opening 36 as indicated in Fig. 7. This opening 36 will not closely hug the pin 34, but will afford a clearance to permit easy flow of the plastic through the opening 36 to accelerate the speed of molding and to permit the use of a reduced pressure on the plastic such that it shall not penetrate through the foundation member at the gate 37. It will be seen that the article produced by this die may be exactly like that shown in Figs. 1 and 2, but this method is not as efficient as that of Figs. 3, 5 and 6.

In Figs. 5 and 6 are shown the respective dies 38, 39 for molding without causing extended contact with the foundation member of the plastic in the gates. These dies include die members 40 and die members 41. Co-operating with the latter are intermediate removable die members 42, 43 respectively which are alike, except that the cavity 44 of the one is smaller than the cavity 45 of the latter. The die members 41 have gates 46 that are openable by removal of the members 42, 43. These gates feed through the orifices 47 in the die members 42, 43. When the molding is completed, the die members 40 may be removed, then the die members 42, 43 are removed, and the plastic gate sections in 46, 47 broken and removed to separate the finished article.

The article molded by the die 38 is less apt to have its front face discolored by plastic, than that of the die 39, because the cavity 44 is spaced from the edge of the cavity of the die member 40.

The several dies described are adapted to be arranged in various ways, for example, according to a system schematically shown in Fig. 8, according to which a plurality of nozzles 48 may feed into a plurality of main gates 49 extending longitudinally of a die plate 50. Interconnecting these main gates are a plurality of secondary cross gates 51 which communicate with die cavities 52. The gates 51 may represent those at 25, 37, and 46. The die cavities may represent any die cavities herein shown. Thus a large foundation member may be molded with the plastic elements in a single operation for the high speed, reliable production of the new articles.

We claim:

1. A device including a textile porous, closed mesh sheet member, a series of sharply defined plastic elements on the front face thereof, a series of anchor elements of plastic material on the rear face thereof, and shanks of plastic material uniformly embedded in the sheet member and extending therethrough, said shanks being integral with said elements and directly interconnecting the elements solely through the sheet member, and relatively straight plastic ribbon-like members at the rear face of the sheet member directly interconnecting the elements and being bonded to the sheet member, said sheet member having the front face free of plastic except for the elements thereon.

2. A device including a porous, closed mesh, textile sheet member, a series of sharply defined plastic elements on the front face thereof, a series of anchor elements of plastic material on the rear face thereof, and shanks of plastic material uniformly embedded in the sheet member and extending therethrough, said shanks being integral with said elements and directly interconnecting the elements solely through the sheet member, said sheet member being concaved into the front plastic elements and being otherwise plane, and plastic straight ribbon-like portions directly interconnecting the elements at the rear face of the sheet member and being bonded to the sheet member, the front face of the latter opposite said portions being free of plastic.
